FUEL BURNER

Filed March 16, 1928

Inventor
O.M. COON,

By *Clarence A. O'Brien*,
Attorney

UNITED STATES PATENT OFFICE

OSCAR M. COON, OF LUBBOCK, TEXAS

FUEL BURNER

Application filed March 16, 1928. Serial No. 262,092.

This invention relates to an improved fuel burner for gaseous fuel which is especially adapted for use in association with furnaces, boilers and the like.

5 What I propose to do is to provide a structure, which in my opinion, is generally an improvement on other known furnace structures patented in this art, or upon burners now upon the market with which I am familiar.

10 The structural features and the relative association thereof which serve to characterize and render this invention individual as compared with known devices, will become more readily apparent from the following description and drawings.

In the drawing:

Figure 1 is a horizontal section through a brick lined furnace showing the improved burner arranged therein.

20 Figure 2 is an enlarged front end elevation of one of the parts of the invention.

Figure 3 is a longitudinal section through the structure seen in Figure 2.

25 Figure 4 is a perspective view of the complete burner unit.

The structure shown in Figures 2 and 3 may be generally designated as a mixer and it is represented in its entirety by the reference character 5. It comprises a special fitting having a flared entrance 6 and a cylindrical neck 7. The neck 7 is fitted telescopically and adjustably upon a fuel conducting tube 8. The adjustment of the fitting on the tube is maintained through the medium of a retaining screw 9. The flared mouth 6 carries a cross piece at its entrance, this being designated at 10, and constituting a mounting for the gas conducting nozzle 11. Here again a set screw 12 is employed for adjustably retaining the gas nozzle in place. Obviously this type of mixer is adaptable for supplying gas under low pressure. Of course the discharge of the gas is regulated by the restricted end of the nozzle and the nozzle is proportioned properly with respect to the flared end to acquire appropriate mixture of the gas and air, the air entering around the nozzle through the flared entrance 6.

60 This mixing device is associated with what may be designated as a burner block or brick

13 composed of high temperature fire clay. The block is general rectangular in configuration and is formed with an elongated slot 14 below which the tube 8 extends. In practice the block occupies the opening in the front wall of the casing 15 of the furnace. Incidentally it may be mentioned that the furnace is provided with a lining composed of a plurality of fire bricks 16 arranged in the approximate manner shown in Figure 1.

65 The mixing device and mounting block therefor constitute a principal part of the burner unit. The remainder of the unit is in the form of an especially designed baffle or obstruction generally designated by the numeral 17. This is made up of a plurality of bricks 18 assembled in spaced relation upon each other as shown plainly in Figure 4. This baffle occupies the position within the fire box of the furnace at about the place indicated in Figure 1.

70 It is obvious that the primary air enters the mixing device through the flared entrance 6 and here it mixes with the incoming gas passing through the nozzle under low pressure as stated. The secondary air passes through the slot 14 above the mixing device and through ducts 14a in the block 13, and at opposite sides of the mixing device as shown in Figure 4. In this way an intimate mixture of fuel is insured. The mixture is ejected against the device 17 in order to provide additional mixing and a combustible fuel for production of an intense flame. When the gas flame and secondary air strike the brick device 17 which is manifestly maintained at a high temperature a secondary combustion of high efficiency for gas consumed takes place.

75 80 85 90 95 90 As is obvious this burner is designed to operate on gas under low pressure and the construction will be approximately 250 cubic feet of 500 cubic feet per hour, and per orifice, depending upon the pressure of gas at said orifice. The principal feature of the invention is the combined action of the baffle or checker device 17 and the special burner.

100 Incidentally the operation of the burner can be varied by appropriate regulations of

the adjustable parts thereof as is evidenced from Figure 3.

It is thought that by considering the description in connection with the drawings a clear understanding of the invention is at hand. Therefore a more lengthy description is regarded unnecessary.

Minor changes in shape, size, and rearrangements of details coming within the field of invention claimed may be resorted to if desired.

Having thus described the invention, what I claim is:—

The combination of a burner open at its opposite ends and containing a comparatively small nozzle whereby a passage for air is afforded between burner and nozzle, and a burner block having an aperture receiving said burner and also having a slot above said aperture and burner and means in its end portions at opposite sides of the burner aperture for the passage of air.

In testimony whereof I affix my signature.

OSCAR M. COON.
